UNITED STATES PATENT OFFICE.

GEORGE YELLOTT, OF TOWSON, MARYLAND.

HYDRAULIC RAM.

SPECIFICATION forming part of Letters Patent No. 447,550, dated March 3, 1891.

Application filed November 3, 1890. Serial No. 370,250. (No model.)

To all whom it may concern:

Be it known that I, GEORGE YELLOTT, of Towson, in the county of Baltimore and State of Maryland, have invented certain Improvements in Hydraulic Rams, of which the following is a specification.

To fully understand the nature of my present invention it must be understood that water moving through the drive-pipe of a hydraulic ram and completely filling it acts as a solid body, and that the power of the ram is limited only by the length of the drive-pipe, the velocity of the moving body of water, and the strength of the apparatus. The capacity of the Montgolfier ram is necessarily limited, in view of the ram-valve closing with a sudden stroke against a solid substance—namely, the material surrounding the valve-opening and which constitutes the valve-seat.

In my present invention, as hereinafter described, the collision of the valve and seat is prevented, and in view of this a ram may be constructed to work satisfactorily of any size or capacity, and a large body of water elevated as easily as a small one.

In the further description of my present invention reference is made to the accompanying drawings, forming a part hereof, and in which—

Figure 1 is a longitudinal section of the improved ram, and Fig. 2 a plan of the same. Fig. 3 illustrates a double ram constructed in accordance with the said invention. Fig. 4 illustrates a modification hereinafter fully described.

Referring to Figs. 1 and 2 of the drawings, A is the ram-chamber, and B and C represent, respectively, the drive and the delivery pipe. D is the delivery-valve, which is situated in the mouth of the air-chamber E. F is the plunger-chamber formed at the end of the ram-chamber opposite to the drive-pipe. It is provided with an outlet a, leading into a waste-chamber G. The discharge-openings from the waste-chamber are denoted by b. H is the plunger which forms the ram-valve, with its lower end adapted to slide in a recess c, situated in the lower part of the plunger-chamber F. This recess and the outlet-opening a are bored so that the plunger will neatly fit therein, and the bottom of the

recess is perforated to discharge any water that may enter it. I is the plunger-stem, and J a disk secured to said stem by means of a collar d and nut f. The disk is somewhat smaller than its chamber, in order to form an annular space g for the waste water to pass. Supposing the plunger to be down in its lowest position, as shown in Fig. 1, the water flowing through the drive-pipe escapes past the disk J until its velocity causes the said disk to ascend and the plunger to be raised. As soon as the upper end of the plunger enters the outlet a the flow of waste water is cut off, the valve D is opened against the air-pressure, and the water enters the air-chamber. As the water in the plunger-chamber becomes quiescent the plunger falls of its own weight, and upon the outlet a being opened the waste flow of water is again established. The waste-water chamber is shown as provided with a cover, which is bolted thereto; but, if desired, this chamber may be opened or uncovered. The advantage of the cover is that it provides means for guiding the plunger-stem.

Referring to Fig. 3, it will be seen that the ram is double, or, in other words, two rams are used, and their plunger-stems connected by a lever K, which has its fulcrum in a lug on the top of the air-chamber. With this arrangement two drive-pipes D are used and two discharge-valves. The object in uniting the plungers of the two rams is to make an alternate action and to enforce a uniform movement of the double apparatus.

Referring to Fig. 4, it will be seen that the disk J is not on the plunger-stem, but on a separate one in an independent chamber, and its stem is connected to the plunger-stem by means of a lever. The operation of this ram is practically the same as that before described, and illustrated in Figs. 1 and 2.

I claim as my invention—

1. In a hydraulic ram, the combination of a ram-chamber with a plunger-chamber in communication therewith, and an outlet leading from the plunger-chamber to a waste-water chamber having a discharge-chamber, a reciprocating plunger-valve situated in the said plunger-chamber, adapted in its upper stroke to enter the said outlet and thereby

cut off the waste water, a stem leading from the said plunger, and a disk operated by the said stem, which disk is of such size as to provide an annular space around it for the escape of water, substantially as specified.

2. In a hydraulic ram, the combination of a ram-chamber having two plunger-chambers in communication therewith, each plunger-chamber having an outlet leading to a waste-water chamber with a discharge-opening, a plunger in each of the said plunger-chambers adapted to have a reciprocating motion and

in its upward stroke to enter the outlet above it, and provided with a stem carrying a disk, around which is an annular space for the escape of water, and a lever which connects the stems of the two plungers, whereby the same have an alternate action, substantially as specified.

GEO. YELLOTT.
